JOINT STRUCTURE FOR PIVOTED TOOLS

Edward Balderstone, Oxford, Pa., assignor to
The S. S. White Dental Manufacturing Company, a corporation of Pennsylvania

Application December 29, 1945, Serial No. 637,861

2 Claims. (Cl. 32—62)

1

My invention relates particularly to that class of forceps that are adapted to be employed by dental practitioners in the extraction of teeth, and is especially directed to the pivotal joint structure connecting the opposed jaw members of such implements.

It is well known that several types of pivotal joints have been employed in the manufacture of such forceps or pliers, including the box joint, the knuckle joint and the so called scissor type joint. The box joint has heretofore been preferred for dental and surgical purposes for the reason that it is deemed to have superior strength and that it was susceptible of being finished to a rounded or oval cross section without introducing any objectionable characteristics. It is obvious that the oval joint structure is superior because of its freedom from projecting edges, its minimum bulk and its consequent smoothness to the feel of the hand of the operator.

It has been known that properly designed forceps embodying the scissors type joint can be made as strong as forceps having a box joint structure, but the scissors type joint was not susceptible of being of rounded or oval configuration for the reason that one of the exposed terminals of the rivet upon which the relatively movable jaw members of the forceps rotate would be caused to expose sharp or ragged edges of the pintle except when the jaw members occupy a fixed position such, for instance, as when normally closed.

The principal objects of my invention are to provide scissors type pliers with the joint structure having a rounded or oval configuration, and having a pintle whose head terminates short of the outer oval surface of the relatively movable jaw member.

Other objects of my invention are to provide forceps of the type contemplated in which its pintle is rigidly engaged with one of the relatively movable jaw members, while its retaining head rotatably terminates within the other of said jaw members, and is covered by a plate or cap formed in integral relation with said jaw member and conforming with the oval or rounded surface of said jaw member in which said head is disposed.

Further objects of my invention are to provide forceps or like implements having relatively movable jaw members joined by a pintle, one of said jaw members being provided with a cylindrical orifice having a ledge affording a seat, the other of said jaw members having a conoidal orifice provided with indentations, a pintle extended through said orifices and having a head rotatably

engaged with said seat while its free end region is upset or riveted to integrally engage the indented walls of said conoidal orifice.

Specifically stated, the form of my invention 5 as hereinafter described comprises forceps having relatively movable jaw members each including a handle and a beak, and being joined pivotally together by a pintle and affording a jointed region whose outer surfaces are rounded, each jaw member of said pliers being provided with a relatively 10 registering aperture, one having a conoidal recess which includes indentations, and the other having a cylindrical recess affording a circular seat and a counter recess arranged to receive a 15 plate or cap, a pintle initially comprising a cylindrical shank which is arranged to be extended through said apertures and an enlarged head fitted in said cylindrical recess while the free end region of said shank is upset to fill said 20 conoidal recess, and a cap initially having an upper conical surface and a lower re-entrant angled conoidal surface is arranged to be forced into said counter recess to cover the head of said pintle.

25 My invention also includes all of the various novel features of construction and arrangement as hereinafter more definitely specified.

In the accompanying drawings, Figure 1 is a plan view of a pair of dental forceps conveniently embodying my invention; Fig. 2 is a side elevational view of the forceps illustrated in Fig. 1; Fig. 3 is an enlarged transverse vertical sectional view taken through the joint of the pliers in the axial plane of the pintle, as indicated by 30 the section line 3—3 in Fig. 1; Fig. 4 is a perspective view illustrating the initial formation of the headed pintle which is shown expanded in Fig. 3; Fig. 5 is a plan view illustrating the initial formation of the pintle head cover or cap shown 35 in Figs. 1 and 3; Fig. 6 is a transverse vertical sectional view of the cap shown in Fig. 5, taken axially therethrough on the line 6—6 in said Fig. 5; and Fig. 7 is a fragmentary inverted plan view of the under jaw member of the forceps showing 40 the indentations in the conical wall of the pivotal aperture extending therethrough.

45 In said figures the forceps illustrated comprise the relatively movable jaw members 1 and 2 pivotally joined together to relatively rock about the axis of the pintle 3. The upper jaw member 1, with reference to the illustrations, includes the handle 4 and the beak 5, and the lower jaw member 2 similarly includes the handle 6 and the relatively opposed beak 7.

50 As illustrated in Fig. 3, the jaw members 1

and 2 are respectively provided with the relatively aligned apertures 8 and 9 through which the shank of the pintle 3 extends. Said pintle is initially formed as shown in perspective in Fig. 4 and is provided with the head 10.

As shown in Fig. 3, the aperture 8 concentrically joins the cylindrical recess 11 which affords the ledge or seat 12 against which the under surface of the pintle head 10 rests, so that the upper surface of said pintle head 10 is disposed well within the body of the upper jaw member 1.

Again referring to Fig. 3, the upper jaw member 1 is also provided with the counter recess 13 preferably having the retaining undercut or groove 14 into which the closure cap 15, initially formed as shown in Figs. 5 and 6, may be forced and thus caused to assume the form illustrated in Fig. 3 to provide a convenient closure integral with the jaw member 1, for the head 10 of the pintle 3.

Referring further to Fig. 3, the pintle aperture 9 in the lower jaw member 2, concentrically joins the conoidal recess 16 which, as illustrated in Fig. 7, includes a circularly arranged series of angular indentations 17 disposed in relatively angular axial planes in the conical wall of said recess 16 and which may preferably extend into the cylindrical wall of said pintle aperture 9, as shown in dotted lines in Fig. 3.

It will be obvious that the lower region of the shank of the pintle 3, shown in Fig. 4, will, when entered through the apertures 8 and 9 and subjected to high pressure or riveting action, conform to the conoidal recess 16 and its indentations 17 into integral relation with the lower jaw member 2.

It has been found in practice that the initial form of the cap 15 may preferably be formed cylindrical with its upwardly extending conical surface 18 and its lower inwardly extending conical surface 19 substantially conforming, whereby to facilitate the conformation under high pressure of said cap 15 to form the closure for the head 10 of the pintle 3, in integral relation with the upper jaw member 1.

My invention is advantageous in that, by constructing the forceps or pliers in the manner herein specifically described, which includes the forming the pintle integral with one jaw member and inclosing the pintle head by a cap or cover which is formed integral with the other relatively movable jaw member, the outer surfaces of the respective upper and lower jaw members may be transversely curved convexedly as illustrated in Fig. 3 without danger of having the edges of the terminals of the pintle exposed

when the plier beaks 5 and 7 are separated to assume an open position.

I do not desire to limit my invention to the precise details of construction and arrangement as herein set forth, as it is obvious that various modifications may be made therein without departing from the essential features of my invention as defined in the appended claims.

Having thus described my invention, I claim:

1. An implement of the class described, comprising a pair of opposed relatively movable jaw members having their outer surfaces convexed transversely, one having an aperture provided with a recess affording a pivot engaging shoulder, and a counter recess providing a circular undercut groove, the other having a relatively aligned aperture joining a conical recess having indentations, a headed pintle extended through said aligned apertures, having its head disposed in said first mentioned recess and engaging said shoulder, and having its opposite end region expanded to conform to said conical recess and indentations, and a closure for said head engaging said groove and conforming to the curvature of the outer surface of said implement.

2. An implement of the class described, comprising a pair of opposed jaw members having their outer surfaces rounded transversely and being relatively movable about a common axis, a headed pintle extended through aligned apertures therein, one having a recess affording a retaining shoulder for relative rotation of the head of said pintle, and the other having a tapered recess into which the opposite end region of said pintle is expanded into rigid non-rotating relation therewith, and a cover for the head of said pintle, conforming to the curvature of the outer surface of said implement, and tightly expanded radially into non-rotatable engagement with the walls of said recess, but rotatable with respect to the head of said pintle.

EDWARD BALDERSTONE.
